UNITED STATES PATENT OFFICE.

HERMANN WASSMUND, ARTHUR MÜLLER, AND ERNST MÜLLER, OF BERLIN, GERMANY, ASSIGNORS TO PATENT-BESTECK-WERKE, G. M. B. H., OF BERLIN, GERMANY, A CORPORATION OF GERMANY.

TANGS.

1,071,282.

Specification of Letters Patent.

Patented Aug. 26, 1913.

Application filed August 23, 1911. Serial No. 645,623.

To all whom it may concern:

Be it known that we, HERMANN WASSMUND, ARTHUR MÜLLER, and ERNST MÜLLER, subjects of the German Emperor, and all 5 residing at Berlin, Germany, have invented certain new and useful Improvements in Tangs, of which the following is a specification.

This invention relates to hollow tangs, 10 and a primary object is to provide an improved attachment exchangeably securing the blade of a knife, fork or the like therein.

The invention substantially consists in 15 connecting the tang of the blade by means of a removable insertion with a known hollow tang consisting of iron or of some other suitable metal, to be secured in the handle, the said insertion filling up the space between the blade-tang and the hollow tang 20 and, if desired, permitting the blade-tang to be immovably secured in the hollow tang by soldering. Such an attachment of the blade-tang is not only cheaper, but also materially more secure than attachments 25 known heretofore, as the said insertion securing the blade-tang is prevented by the hollow tang from deviating laterally and the handle is relieved from any possible 30 lateral pressure exerted by the insertion.

Three embodiments of the invention are represented by way of example in the accompanying drawing, wherein:

Figures 1 and 2 are vertical sections taken 35 in planes at right angles to one another showing one form of the improved attachment, Fig. 3 is a like view showing another form, and Fig. 4 a like view showing a third form.

Referring firstly to Figs. 1 and 2, *a* designates a hollow tang provided with the bolster *b*. The blade *c* is held in position in a known manner in the slot *g* in the bolster and its tang *d* projects into the hollow tang. 40 The blade-tang *d* is attached in the hollow tang in this form by means of insertions composed, for example, of a well-known metal composition *e* filling up the intermediate space between the blade-tang and the 45 hollow tang. In order to give the metal composition a firm hold, the tang *d* is pro-

vided with notches *f*. Such notches may also be provided in the interior wall of the hollow tang *a* if desired. Since the composition liquefies at a certain relatively low 55 temperature, the insertion can be melted by exposing the attachment to this temperature and the blade can thus be at once exchanged.

Secondly, in the illustrative embodiment 60 according to Fig. 3 the intermediate space between the hollow tang *a* and the blade-tang *d* is occupied by two insertions *m*, *n* formed to fit in the hollow tang and connected in suitable manner with both the 65 hollow tang and the blade by soldering. Obviously, this arrangement also at once admits of the blade *c* being readily exchanged.

Thirdly, referring to Fig. 4, the form here 70 shown is distinguished from those described above merely by the insertion being united with the blade-tang to form a plug *h* which fits in the hollow tang *a* and is connected therewith by soldering. 75

We claim:

The combination with a blade having a tang on one end thereof and the sides of the blade and tang being continuously flat and smooth in opposite directions from the 80 juncture thereof, of a handle tang being of one piece, forming a hollow body and having an opening to receive the blade tang and of sufficient size to provide clearance between the blade tang and the wall of said 85 opening, said handle tang having an outwardly projecting bolster at the blade end thereof and formed of material of great resistance and high melting point, and a metallic insertion body removable by melting 90 at a comparatively low temperature, filling said opening surrounding said blade tang, substantially as described.

In testimony whereof, we affix our signatures in the presence of two witnesses.

HERMANN WASSMUND.

ARTHUR MÜLLER.

ERNST MÜLLER.
